Patented May 2, 1967

207,542

PORTABLE AIRPLANE TOY

Robert H. Wendt, Evanston, Ill.
(7567 Lincoln Ave., Skokie, Ill. 60076)

Filed Mar. 28, 1966, Ser. No. 1,662

Term of patent 14 years

(Cl. D34—15)

FIG. 1 is a side elevational view of a portable airplane toy, embodying my new design, the other side is identical in appearance;

FIG. 2 is a front elevational view;

FIG. 3 is a top plan view; and

FIG. 4 is front elevational view, with the wings folded up;

I claim:

The ornamental design for a portable airplane toy, as shown and described.
